BOMB SWAY BRACE

Marion B. Crawford, Seattle, Wash., assignor to
 Boeing Airplane Company, Seattle, Wash., a
 corporation of Washington

Application January 16, 1934, Serial No. 706,843

19 Claims. (Cl. 244—1)

Bombing airplanes customarily carry bombs beneath the wing or fuselage, where, with their releasable securing means and braces ordinarily fixed in position to prevent them from swaying 5 from side to side, they constitute a drag upon the airplane, and even after the bombs have been released the sway braces, still projecting from the streamlined contour, produce a very considerable drag. After the bombs have been 10 released it is of the utmost importance that the bomber be able to get away as rapidly as possible, for it is only by its speed that it can hope to escape enemy fighter planes. It is highly desirable, therefore, that all such projecting parts, especially the sway braces which produce 15 drag, be withdrawn within the streamlined contour, or in some manner that the streamlined contour be restored, following the release of the bombs. Since the pilot has his hands full at 20 such time in maneuvering his plane and in watching for enemy pursuit ships, it is also desirable that no burden be placed on the pilot or other members of the crew of the bomber, who are likewise busy, to think and act to restore this 25 streamlined contour, and it is therefore desirable that such means for restoring the streamlined shape be automatically operable.

My invention has the accomplishment of the above aims as its principal object. It is also 30 an object, in instances where an airplane is equipped to carry a number of bombs that each of the means for restoring the streamlined shape be operable independently of all others, so that if only a portion of the bombs are released 35 the brace members and the like which engaged the bombs which were released can be withdrawn into the streamlined shape, and the latter be restored and drag eliminated or lessened that much.

40 It is a further object, especially where the airplane is equipped for supporting a plurality of bombs, to provide such brace means which are urged into engagement each with its respective bomb, and retractable independently of all others, 45 to provide means whereby all such means may be relaxed simultaneously to facilitate the securing of the bombs, and further, which may be simultaneously brought into operation so that each means will then brace its respective bomb, 50 regardless of variations in their size.

It is a further object to provide a bomb sway 55 brace means for one or a plurality of bombs, which shall be simple in construction and easily operable, self-conforming to different sizes of bombs, and one which can be readily incorporated into an airplane structure, lying within the streamlined shape of the structure except as the brace means are projected into the wind stream to brace the bombs supported outside 60 the streamlined structure.

Other objects will be ascertained from the attached drawings and from this specification, especially such as relate to structural details.

My invention comprises the novel sway brace means, both of each individual unit and of the plurality of units as a whole, and the novel construction and assemblage of parts to the end of accomplishing the above and other objects.

In the accompanying drawings I have shown my invention embodied in a typical form, as now 10 preferred by me.

Figure 1 is a top plan view of the device as a whole, the operating handle being omitted, and with parts shown in the relaxed position, ready for the securing of bombs.

Figure 2 is a view similar to Figure 1, but showing parts in the operative position.

Figure 3 is a side elevation, with parts broken away, of the device as a whole, showing parts in the operative position.

Figure 4 is a transverse section on the line 4—4 of Figure 3, and Figure 5 is a similar section on the line 5—5 of Figure 3.

Figure 6 is an underside view in perspective of the center section of a typical bomber, showing 25 my device incorporated therein.

In Figure 6 the bombs B2, B3, B4 and B5 are shown supported beneath the center section of the wing 9. It will be understood, of course, 30 that they might be supported from the fuselage 90, or from any suitable part of the airplane structure, which part would usually be streamlined. In any instance they are supported outside of the streamlined contour in the wind stream. The manner of their securing is immaterial in so far as my invention is concerned, and is illustrated only diagrammatically at 91 in Figure 3. In this same figure the skin 35 92 of the wing 9 is illustrated in section.

To prevent the bombs from swaying from side to side I employ brace members each comprising 40 a plate 1 pivoted at 10 within the airplane structure on an axis extending longitudinally of the airplane, whereby the braces will swing transversely. Each plate may be apertured for lightness, but in effect it constitutes a flat surface directly opposed to the wind stream, which causes an appreciable amount of drag. To eliminate this drag I provide means whereby as each bomb is released the pair of brace members, one 45 engaging each side of such bomb, is withdrawn within the airfoil or streamlined shape, and to this end I provide on each plate 1 an arm 11 which is pivotally connected at 12 to a clip 22 which is mounted and slidable upon a rod 2. Two such rods are employed, which to distinguish them are designated 2 and 2', and these are slidable lengthwise in guides 20 supported from the 50 airplane structure. As a convenient means of supporting the rods and the brace members 1 I 55 60

provide a channel structure 3, the pivots 10 being supported in the flanges of the channel, and the guides 20 being mounted on the web thereof. This channel 3 may conveniently be secured in any suitable manner, as by the rivets 21, which connect its outspread flanges 30 to the skin 82 of the wing or fuselage. Connection is established from each of the members 1 to a rod 2 or 2' by means of the clips or arms 22 hereinafter referred to, these clips being freely slideable along the respective rods. The reason for employing two rods is that the two brace members 1 of each pair swing oppositely on their pivots toward each other, and engage on opposite sides of a bomb, hence by movement of one of the clips 22 in one direction and the other clip in the opposite direction the two brace members of a pair can be moved toward each other and through the aperture 83 in the wing skin 20 through which they project, into the streamlined shape. They may be formed to substantially close this aperture when retracted, as seen in the middle pair of Figure 3, whereby they not only lessen or eliminate the drag caused when they project, but substantially restore the streamlined shape.

It would be possible to provide a rod such as 2 for each of the brace members 1, but it is unnecessary to do so, and it eliminates weight to provide only the two of them, the rod 2 and the rod 2', and each such rod may be caused to urge each one of the brace members 1 which is connected thereto against the side of a bomb by such means as an extension coil spring 4, one end of which is connected to the rod, as indicated at 40, and the other end of which is connected to the clip 22, as indicated at 41. By moving the point 40 away from the point 41, the spring is tensioned and the brace member connected thereto is caused to be drawn against the side of the bomb. If, however, the bomb is released the extended spring will act to throw the brace member 1 upward within the wing. If, on the other hand, the point 40 is moved toward the point 41, and the movement of the latter point and of the associated brace member is stopped by reason of the engagement of the pivot 12 at the end of an arcuate slot 33 in the channel member 4, then the tendency to withdraw the brace members is relieved, and the springs are relaxed, whereupon a bomb may readily be secured in place beneath the wing. Notwithstanding that the device may be so operated that all the brace members are relaxed simultaneously, it will be clear that each individual pair of brace members may be withdrawn independently of all other pairs, immediately upon release of the bomb with which they are associated, so long as its springs remain extended.

In order to accomplish such relaxation and extension of the several springs, means are provided to move the rods 2 and 2' longitudinally, and to this end there may be formed upon each of them a series of rack teeth 25 (see Figure 1) and these portions of the rods may be guided in a guide 26, whereon is journaled a rack pinion 27, with which is associated a handle 28, and a spring pawl 29 is provided, engageable with the pinion 27 and operable to hold the springs extended, or when released from the pinion, to permit the springs to relax as they draw the rods from the position of Figure 2 to that of Figure 1.

The device is supported, as described, preferably within the streamlined form of the airplane structure, though the manner of its support is im-

material. The channel member 3 in effect forms part of the airplane structure, at least for the purposes of supporting the braces 1. The springs are relaxed, the bombs are secured in place, and the springs are then extended by rotating the handle 28, the pawl 29 being engaged with the pinion 27. Now as each bomb is released the extended spring associated with the corresponding braces causes these braces to be withdrawn, yet the force of all other springs is retained unchanged so long as the bomb associated therewith remains in place.

It may be pointed out here that the physical withdrawal of the braces is only one of a number of ways in which the drag of such members can be lessened. They might be turned into a position where their drag is lessened without any or without entire withdrawal thereof, or the streamlined structure may be altered by the projection of devices such as fairing means to include the braces, after the bomb has been released. I do not desire to be limited merely to withdrawal of the braces, whether partial or complete, other than as required by the appended claims. Furthermore, the movement of the braces might be otherwise than a pivotal movement, and this is within the intended scope of my invention. The particular means for operating the braces might be varied widely. It is my intention to claim broadly any means operable following release of a bomb (especially such means as are then automatically operable), to decrease the drag caused by the brace means or other means associated with the bomb, whether by movement thereof into a position of less drag, or by their complete withdrawal or shielding.

What I claim as my invention is:

1. In combination with an airplane structure whereon are means to releasably support bombs, means separate from the bomb supporting means to brace such bombs, said brace means projecting, when in operative position, into the wind stream, and means operable following release of its bomb to lessen the drag of said brace means.

2. In combination with an airplane structure, means to brace bombs, releasably supported thereon, against swaying, said means projecting from the airplane structure into the wind stream, and means automatically operable upon release of a bomb to lessen the drag of said brace means.

3. In combination with an airplane structure, means to brace bombs, releasably supported thereon, against swaying, said means, when in operative position projecting from the airplane structure into the wind stream, and means automatically operable upon release of a bomb to move said brace means from such operative position into a position wherein its drag is lessened.

4. In combination with a streamlined structure, means to brace bombs which are releasably supported thereon, against swaying, said means projecting from the structure into the wind stream, and means automatically operable upon release of a bomb to withdraw said brace means to restore the streamline thereof.

5. In combination with an airplane structure, a pair of members mounted thereon and in operative position cooperatively engageable with a bomb releasably mounted thereon to brace the bomb against swaying, and projecting, when in such operative position, into the wind stream, and means operable following release of such bomb to lessen the drag caused by such members.

6. In combination with an airplane structure, a pair of brace members pivotally mounted at

5 points spaced transversely of the airplane structure, on axes extending longitudinally, and spring means normally acting upon said brace members to swing the latter into the airplane structure, and holding them, when a bomb is disposed therebetween, against opposite sides of the bomb.

10 7. In combination with an airplane structure, a pair of brace members pivotally mounted at points spaced transversely of the airplane structure, on axes extending longitudinally, spring means normally acting upon said brace members to swing the latter into the airplane structure, and holding them, when a bomb is disposed therebetween, against opposite sides of the bomb, and 15 means to relax said spring means to facilitate securing of the bomb in such position.

15 8. In combination with an airplane structure, a plurality of means each operable to brace its respective one of a plurality of bombs which are 20 by other means releasably supported from the airplane structure, said brace means projecting, when in operative position, into the wind stream, and means operable following release of any given bomb to lessen the drag of the corresponding brace 25 means.

25 9. In combination with an airplane structure, a plurality of means each operable to brace its respective one of a plurality of bombs which are 30 releasably supported from the airplane structure, said means projecting, when in operative position, into the wind stream, and means automatically operable upon release of a bomb, to move the corresponding brace means into a position wherein its drag is lessened.

35 10. In combination with an apertured streamlined structure, a plurality of means each operable to brace its respective one of a plurality of bombs which are releasably supported from said structure, said means, in such operative position, projecting through the apertures in the structure 40 into the wind stream, and means operable upon release of any bomb to move the corresponding brace means into the structure, to substantially close the corresponding aperture and restore the streamline form of the structure.

45 11. In combination with an airplane structure, a plurality of means each engageable with its respective one of a plurality of bombs releasably supported from the airplane structure, to brace such bomb against swaying, and means acting 50 upon each of said brace means to cause the latter to conform automatically and individually to various sizes of bombs, said means being further and automatically operative, independently of the other brace means, and following release of its corresponding bomb, to lessen the drag caused by the projection of such bracing means into the air stream.

55 12. In combination with an airplane structure, a plurality of means each engageable with its respective one of a plurality of bombs releasably supported from the airplane structure, to brace such bomb against swaying, spring means urging each such brace means against its respective bomb, and means to relax the spring means of all brace means simultaneously, to facilitate securing of the bombs.

60 13. In combination with an airplane structure, a plurality of pairs of brace members pivotally mounted upon and in operative position projecting from the airplane structure, spring means acting upon said members when projected to urge the two members of each pair into engagement with opposite sides of its respective one of a plurality of bombs releasably supported from

the airplane structure, and further operable, independently of all other pairs of brace members, to retract its associated brace members within the airplane structure.

65 14. In combination with an airplane structure, a plurality of pairs of brace members pivotally mounted upon and in operative position projecting from the airplane structure, spring means acting upon said members when projected to urge the two members of each pair into engagement with opposite sides of its respective one of a plurality of bombs releasably supported from the airplane structure, and further operable, independently of all other pairs of brace members, to retract its associated brace members within the 15 airplane structure, and means to simultaneously relax the spring means of all pairs of brace members, to facilitate securing of the bombs to the airplane structure.

20 15. In combination with an apertured streamlined airplane structure, a plurality of pairs of brace members of generally flat shape disposed transversely of the air stream, and pivotally mounted upon the airplane structure upon longitudinally extending axes, to swing through the 25 apertures into the wind stream, thereby to engage the two members of each pair with opposite sides of its respective one of a plurality of bombs releasably supported from the airplane structure, and in the wind stream, and means operable 30 following release of any bomb to withdraw its brace members, independently of all other brace members through their respective apertures, thereby to restore this portion of the streamline form of the airplane structure.

35 16. In combination with a streamlined airplane structure whereon a bomb is releasably supported in the wind stream, means projecting from the streamline form and engageable with such bomb, while thus supported and means operable following the release of such bomb to 40 restore the streamline form of the airplane structure.

45 17. In combination with a streamlined airplane structure whereon a bomb is releasably supported in the wind stream, means projecting from the streamline form and engageable with such bomb, while thus supported, and means operable automatically by release of such bomb to move said projecting means into a position 50 wherein its drag is lessened.

55 18. In combination with an airplane structure, and with means thereon to suspend a bomb freely beneath the airplane structure, for release therefrom, means engageable with such a bomb to brace the bomb against swaying, and means acting upon said brace means to cause the latter to conform automatically to any one of various sizes of bombs, said means being further and automatically operative, following the release of the corresponding bomb, to lessen the drag caused by the projection of the bracing means into the air stream.

60 19. In combination with an airplane structure, and with means thereon to suspend a bomb freely beneath the airplane structure, for release 65 therefrom, means engageable with such a bomb to brace the bomb against swaying, means acting upon said brace means to cause the latter to conform automatically to any one of various sizes of bombs, and means to render inoperative the 70 bracing means, at will.
